UNITED STATES PATENT OFFICE.

EBENEZER N. AIKEN, OF AVALON, PENNSYLVANIA, ASSIGNOR TO THE McCASKEY REGISTER COMPANY, OF ALLIANCE, OHIO, A CORPORATION OF OHIO.

FILING APPLIANCE.

1,298,150.

Specification of Letters Patent.

Patented Mar. 25, 1919.

Application filed October 8, 1915, Serial No. 54,745. Renewed September 11, 1916. Serial No. 119,599.

To all whom it may concern:

Be it known that I, EBENEZER N. AIKEN, a citizen of the United States, residing in the borough of Avalon, in the county of 5 Allegheny and State of Pennsylvania, have invented certain new and useful Improvements in Filing Appliances, of which the following is a specification.

The invention relates to a filing appliance 10 for sales bills used in the duplicating, forwarding, one-writing system of keeping credit accounts; and the object of the invention is to provide code devices for indicating but not stating the amount or time of 15 credit which may be extended to a particular customer, without interfering with a free and ready inspection of the details of the account current.

Filing appliances of this kind are frequently made with a series of normally upright holding leaves or frames hinged together at their lower ends and mounted in 20 a suitable case so that the holders can be singly or collectively swung forward on 25 their hinged ends into reclined position.

Such holders are usually provided on each side with a series of longitudinal ribs or portions forming a series of pockets in which sales bills may be filed; and each 30 pocket is usually provided with one or more spring clips or clamps behind which a pack of sales bills may be entered and retained.

These bill clamps are frequently made of 35 spring wire bent to form two lateral sides or legs yoked together at the top and having laterally extending spring coils formed on the lower ends, the outer ends of such coils being secured to the back or wall of the bill holding frame; and finally, the sides or 40 legs of the bill clamps are frequently secured together and strengthened, intermediate their ends, by a connecting plate, upon which plate is mounted or displayed a number or other character indexing or designating 45 the name of the particular customer whose sales bills are intended to be filed behind the bill clamp carrying this number.

The object of the present invention is attained by providing a signaling device 50 adapted to be readily applied to the bill clamp at or near the index plate; such signaling device being provided on its face with a suitable code color or other insignia to indicate without stating the amount of

credit intended to be extended to the customer whose index number appears on the connecting plate on the bill clamp to which the signaling device is applied.

A preferred embodiment of the invention, thus set forth in general terms, is illustrated in the accompanying drawings, forming part hereof, in which—

Figure 1 is a fragmentary perspective view of a filing appliance showing the relative location and arrangement of the case and the bill holders therein;

Fig. 2, a face view of one of the bill holding frames; and

Fig. 3, a detached perspective view showing fragmentary parts of the sides or legs of a bill clamp with the connecting plate applied thereto, and a signal device in position for having its stem inserted within the socket formed by the flanges of the plate.

Similar numerals refer to similar parts throughout the drawings.

The filing appliance includes the case 1 having an index table 2 formed therein and a series of bill holding frames 3 pivotally mounted therein; each bill holding frame being provided with suitable longitudinal ribs 4 at the side edges and 4^a intermediate thereof, and with the hinge bars 5 and rim bars 5^a, all of which form the recesses 6 in 85 which sales bills are adapted to be filed.

The bill clamps 7 may be made of spring wire with the legs 8 on each side connected together by the yoke 9 at the upper free end and secured to the back or wall 10 of 90 the bill holding frame by means of the fingers 11 on the outer ends of the laterally extending spring coils 12 formed on the lower ends of the legs.

In the preferred form of bill clamp a connecting plate 13 is provided intermediate the ends of the clamp, usually in the middle portion thereof, which plate may be secured to the legs of the clamp by having its ends bent and looped around the wire of the 100 legs, as shown at 14 in Fig. 3, these bends being made in such a manner as to rigidly secure the parts together for the purpose of strengthening the bill clamp and holding its legs and their connecting yoke in the same 105 plane.

In the embodiment of the present invention, illustrated in the drawings, the signal

device 15 is made of a plate or sheet of metal, or other stiff material, having a relatively narrow lower end or shank 16 and a wider upper display portion 17, the side edges 18 of which may be inclined upward and outward and the top edge 19 of which may be curved or crowned, as may be desired.

When made in this form, the signal device is adapted to have its lower end or shank inserted between the legs of the bill clamp in the socket formed behind the body of the connecting plate by the bent ends thereof extending around the legs of the clamp, so that the enlarged upper display portion of the signal device will appear immediately above the index plate, as shown more particularly in Fig. 2.

The exposed face of the several signal devices are finished or provided with different code colors, or other distinguishing features, for imparting particular information, as for instance, the device at A in Fig. 2, may be finished in red, to indicate a credit limit of \$25.00; the device shown at B may be finished in blue, to indicate a credit limit of \$10.00; the device at C may be finished in yellow, to indicate a credit limit of \$15.00; and the device at D may be finished in black, to indicate a credit limit of \$30.00; in each case indicating to the clerk that the account of the customer whose bills are filed behind the particular bill clamp, has reached or exceeded the amount of credit intended to be extended.

The exposed face of the signal device can also be provided with code characters to designate a time limit for credits; as for instance the letter X may be used to indicate that the account is to be settled weekly, the letter Y may be used to indicate that the account is to be settled bi-weekly or semi-monthly, and the letter Z may be used to indicate that the account is to be settled monthly, irrespective of the amount of the account at the end of the stated period; it being evident that an amount limit of credit and a time limit of credit can be designated either jointly or severally on signal devices, as may be desired.

When a customer begins trading with the merchant upon a credit basis, and the amount of credit to be extended is agreed upon, or otherwise determined, the merchant will select a signal device having the particular color or other designation which indicates such credit limit, and will apply or secure the same to the bill clamp which carries the index number of the customer in question. The signal device remains on the bill clamp as long as the customer continues dealing on a credit basis, unless perchance by reason of his varying fortunes, his credit limit is either reduced or increased, whereupon the original signal de-

vice is replaced by another one properly indicating the new credit limit.

By these means it is evident that the merchant does not need to keep any additional record or list of the varying amounts of credit to be extended to different customers, nor does he need to give any special instructions on this subject to his clerks or other employees, for the reason that whenever a customer is waited upon and the clerk undertakes to file the duplicate sales bill behind the clamp carrying the customers index number, the eye of the clerk necessarily sees the signal device during the same glance by which the index number is located, and is signaled at once, without any previous instructions or further inquiry, just what amount of credit may be extended to that particular customer.

It is evident that by locating the credit limit signal device in proximity to the index number, which in turn is located centrally on the bill clamp, these signals are located near the middle of the sales bill which is filed behind the clamp, and are usually so near to the figures on the bill showing the total amount of the account, that the index number, the credit limit signal and the total amount of the account can all be seen with a single glance of the eye. This arrangement greatly reduces the time and effort required to obtain and coördinate these several items of information, and reduces to a minimum the possibility of error in connection with the account, or in extending credit beyond the amount or time limit.

Filing appliances of this character are widely used in general stores, in manufacturing and mining communities, wherein the workmen are mostly wage earners receiving periodical payments, and wherein it is customary for the merchant to extend credit to different customers in proportion to their accustomed earning power and the average amount of their wage or salary. In such communities the difference between success and failure upon the part of the merchant depends largely upon keeping the accounts of his several customers within predetermined limits.

The present invention is well adapted to accomplish this purpose automatically after the account is started, without any personal attention or instructions being given by the merchant, or any special investigation or inquiry being made by the clerk.

I claim:

1. A filing appliance including a bill holder, a bill clamp having an index number thereon, and a code device designating a credit limit on the bill clamp in proximity to the index number.

2. A filing appliance including a bill holder, a bill clamp having a centrally lo-

cated index number thereon, and a device designating a credit limit on the bill clamp in proximity to the index number.

3. A filing appliance including a bill holder, a series of bill clamps having index numbers thereon, and a device designating a credit limit adapted to be applied to any one of the bill clamps in proximity to the index number thereon.

10 4. A filing appliance, including a bill holder, a bill clamp made of spring wire with an index plate connecting the sides of the clamp intermediate the ends thereof, and a device designating a credit limit detachably engaged with the connecting plate.

5. A filing appliance including a bill holder, a bill clamp made of spring wire with a connecting plate having its ends bent around the wire sides of the clamp, and a 20 device designating a credit limit having a stem adapted to be secured in the socket formed by the bent ends of the connecting plate.

6. A filing appliance including a bill holder, a bill clamp made of spring wire with a connecting plate having its ends bent around the wire sides of the clamp, and a 25

signal device having a stem adapted to be secured in the socket formed by the bent ends of the connecting plate.

7. A filing appliance, including a bill holder, a bill clamp made of spring wire with an index plate connecting the sides of the clamp intermediate the ends thereof, and a signal device detachably engaged with the connecting plate.

8. A filing appliance including a bill holder, a series of bill clamps having index numbers thereon, and a signal device adapted to be applied to any one of the bill clamps in proximity to the index number thereon.

9. A filing appliance including a bill holder, a bill clamp having a centrally located index number thereon, and a signal device on the bill clamp in proximity to the index number.

10. A filing appliance including a bill holder, a bill clamp having an index number thereon, and a signal device on the bill clamp in proximity to the index number.
